UNITED STATES PATENT OFFICE.

WILLIAM J. LEARY, OF BUFFALO, NEW YORK.

PAVING BRICK OR BLOCK.

SPECIFICATION forming part of Letters Patent No. 710,062, dated September 30, 1902.

Application filed February 10, 1902. Serial No. 93,284. (No model.)

To all whom it may concern:

Be it known that I, WILLIAM J. LEARY, a citizen of the United States, residing at Buffalo, in the county of Erie and State of New York, have invented new and useful Improvements 5 in Paving Bricks or Blocks, of which the following is a specification.

This invention relates to a paving brick or block of that kind which is provided with a 10 cavity or hollow in its under side or base which when the brick is set on its supporting foundation forms a chamber for air which acts as insulation and prevents the disturbance of the foundation by heat and cold. 15 When such bricks or blocks are laid or set on the cement or plastic foundation provided therefor, the under faces of the bricks are embedded somewhat in the soft foundation, so that portions thereof extend up into the 20 air-chamber. To enable this, the bricks are provided with air-vent openings to permit the escape of the displaced air.

The object of the present invention is to produce a paving brick or block having an air- 25 chamber in its base or under side and an air-vent opening or channel extending through the central or main body portion of the brick or block and to provide means for preventing the thin cement or grout which is usually 30 poured into the crevices or spaces between the bricks from filling the air-chambers, and thus destroying the insulating properties of the brick or block.

In the accompanying drawings, Figure 1 is 35 a sectional view of a section of pavement constructed of bricks or blocks embodying the invention. Fig. 2 is a plan view, on a reduced scale, of a section of pavement before the grout is filled in. Fig. 3 is a bottom plan view of 40 one of the paving bricks or blocks. Fig. 4 is a plan view, on a reduced scale, of a section of pavement before the grout is filled in, showing paving bricks or blocks of slightly different conformation.

45 Like letters of reference refer to like parts in the several figures.

A represents the paving brick or block, which may be formed of any suitable material—such, for instance, as clay. The brick 50 may be of any desired conformation, preferably being polysided and provided with a flat or plane top or upper face and a flat bottom

face. The brick is provided in its base or under side with a cavity or hollow B and with an open-ended hole or channel C, which extends through the body or central portion of the brick from the top face thereof into the cavity B.

When a pavement is constructed, a suitable foundation layer of broken stone, concrete, or the like D and an upper layer of hard-setting cement, mortar, or other suitable plastic material E are provided. The bottom faces of the bricks are pressed down into the upper layer of cement or plastic material, so that the same enters somewhat into the cavities B in the bricks. The air-vent openings or channels permit the displacement of the air and the rising of the cement in the cavities. The bricks are thus held firmly in 70 position from lateral displacement when the layer of cement or plastic material sets. After the bricks are set in the cement a thin cement, grout, or analogous material is poured into the crevices or spaces left between the 75 adjacent bricks, and to afford these spaces and at the same time make a rigid durable pavement the lower portions of the sides of the bricks are vertical and abut against each other, while the upper portions of the bricks 80 are reduced in diameter—for instance, by beveling the upper portions of their sides, as shown at F.

When the cement is poured over the pavement to fill the spaces between the bricks, it 85 enters the air-vent openings or channels and runs into the air-chambers B. To prevent the cement from filling the chambers and destroying the insulating properties of the brick and also to prevent the waste of the thin cement or grout, the brick is provided with a teat or projection G, which extends down into the air-chamber toward the open lower end thereof, but terminates above the plane of the bottom face of the brick. The air-vent 90 opening or channel passes through this teat and opens at the lower end thereof into the air-chamber. When the thin cement or grout rises in the air-chambers to the lower end of the teat, it seats or closes the vent-opening. 100 Air is thus confined in the chamber between the plane of the lower end of the teat and the top of the cavity.

A brick made as above described, with the

air-vent opening or channel extending through the main body or central portion thereof, is desirable, for when the brick is being dried or burned the central opening permits the material of the brick to shrink evenly toward the center opening, which prevents the surface from "season checking" or cracking, thus enabling the production of a better quality of brick. The teat enables the air-vent opening or channel to be placed in the center of the brick without permitting the cement to fill the air-chamber, so as to expel the air therefrom and destroy the insulating properties of the brick. Thus the brick acts as a good non-conductor of heat and cold, and the life of the foundation, and consequently of the pavement, is greatly prolonged.

The bricks shown in Fig. 4 are similar in construction to those shown in the other figures, with the exception that they are of different external conformation; but the external shape of the brick forms no essential part of the present invention, and they may be made square, hexagonal, octagonal, or in any other preferred shape.

I claim as my invention—

1. A paving brick or block provided with

an air-chamber, a teat extending into said air-chamber and an air-vent opening extending through the brick or block and through said teat, substantially as set forth.

2. A paving brick or block provided in its underface with a cavity forming an air-chamber, a teat extending into said cavity and terminating above the base of the brick, and an air-vent opening extending through the body of the brick or block and through said teat, substantially as set forth.

3. A paving brick or block formed with an open cavity in its bottom or base and with a central teat extending down into said cavity and terminating above the bottom face of the brick, and an air-vent opening extending vertically through the central portion of the body of the brick and through said teat, said air-vent opening being open at its upper and lower ends, substantially as set forth.

Witness my hand this 6th day of February, 1902.

WILLIAM J. LEARY.
